UNITED STATES PATENT OFFICE.

SETH M. MORRIS, OF GALVESTON, TEXAS, ASSIGNOR TO GERMICIDE GAS COMPANY, OF AUSTIN, TEXAS, A CORPORATION OF TEXAS.

FORMALDEHYDE-FUMIGATOR.

SPECIFICATION forming part of Letters Patent No. 746,781, dated December 15, 1903.

Application filed March 7, 1903. Serial No. 146,744. (No model.)

To all whom it may concern:

Be it known that I, SETH M. MORRIS, a citizen of the United States, residing at Galveston, Galveston county, State of Texas, have 5 invented a certain new and useful Improvement in Fumigators and Gas-Generators, of which the following is a full, clear, and exact description, such as will enable others skilled in the art to which it appertains to make and 10 use the same, reference being had to the accompanying drawings, forming part of this specification, in which—

Figure 1 is an elevation, partly in section, certain of the parts being broken away; and 15 Fig. 2 is a fragmentary bottom plan view, partly in section.

My invention relates to improvements in fumigators and gas-generators, the present apparatus being particularly adapted for producing 20 formaldehyde gas and for fumigating a room or the like by the use of such gas.

One object of the invention is to provide a construction by means of which gas can be rapidly generated by the use of an oxidizing 25 or catalytic device. A further object is to provide means whereby gas can first be generated in a relatively dry condition and moisture can then be added to the gas; and a further object is to provide an apparatus 30 by means of which the wood-alcohol or other suitable liquid can be rapidly evaporated, the evaporation being substantially uniform over the whole surface from which evaporation takes place.

To these ends and also to improve generally upon apparatus of the character indicated, my invention consists in the various matters hereinafter described and claimed.

Referring now more particularly to the 40 drawings, the reference-numeral 1 is applied to supporting-standards, here shown as four in number, which standards are preferably provided with suitable feet and serve to support the various parts of the present device, 45 and 2 is a font supported upon said standards near their lower ends and having its top open, said font being adapted to receive the wood-alcohol or other liquid to be employed in the production of the gas.

3 indicates generally the oxidizing or cata-

lytic device, which is adapted to be supported above the liquid in the font.

4 represents an adjustable smothering-plate, and 5 is an open water-pan, which is supported above the font 2 and the oxidizing 55 device 3.

In the general operation of my apparatus wood-alcohol or other suitable liquid is placed in the font, the smothering-plate is supported in elevated position, as shown by full lines in 60 Fig. 1, and the oxidizing device is also supported in elevated position, as shown by dotted lines in Fig. 1. The vapor arising from the font being ignited, the flame plays upon the said oxidizing device and is permitted to 65 continue to do so until the oxidizing or catalytic material is sufficiently heated, this material being in practice heated to such an extent that it is caused to glow. The oxidizing device is then lowered to the position shown 70 by full lines in Fig. 1, and in most instances this will be sufficient to extinguish the flame from the alcohol. Should the flame not be extinguished by the oxidizing device, however, the smothering-plate is lowered to the 75 position shown by dotted lines in Fig. 1 and after the flame has been extinguished said smothering-plate is returned to its elevated position. The heated oxidizing or catalytic material causes the alcohol to continue to 80 evaporate, the alcohol-vapor passing through the oxidizing material and undergoing oxidation, whereby the wood-alcohol vapor is transformed into formaldehyde gas, the oxidation being sufficient to cause the oxidizing or catalytic material to continue to glow and to thus cause the alcohol to continue to 85 evaporate. This general action is well understood and will therefore not be further described in this specification.

It is well known that dry formaldehyde gas has greater penetrating powers than moist formaldehyde gas, and it is also well known that moist formaldehyde gas has greater germicidal powers than has dry formaldehyde gas. In fumigating by the use of formaldehyde gas it is a common practice to permit a considerable quantity of water-vapor to discharge into the compartment being fumigated in order to secure the germicidal ef- 90 95 100

fect of moist formaldehyde gas; but this wa-
ter-vapor forms a water seal upon articles in
the room, and thus prevents the thorough
penetration of the gas. In the present ap-
paratus the water-pan 5 is supported above
the font and the oxidizing device and in the
direct path of the heated gas radiating from
the apparatus. When the generation of gas
is commenced, the water is of course cold or
cool, and as the water-pan is supported a con-
siderable distance above the font and the ox-
idizing device no evaporation of water takes
place until after the apparatus has been in op-
eration for some length of time. During this
time and before the evaporation of the water
commences a sufficient amount of formalde-
hyde gas has been generated to thoroughly
penetrate the substances in the compartment
being fumigated, and after this penetration
by the gas the water commences to evapo-
rate and charges the room with moisture.
In this manner I am enabled to take advan-
tage of the penetrating powers of the dry gas
and to also take advantage of the germicidal
powers of the moist gas, the initial produc-
tion of dry gas and the later mixture of mois-
ture with the gas being made possible with-
out any action on the part of an attendant,
whereby the desired results can be obtained
by merely starting the action of the appa-
ratus and then leaving the same.

Such being the general construction and
operation of the present apparatus its details
are now to be considered. The font 2 is pro-
vided with a vertical central air-tube 6 and
has its peripheral wall at a point above
said air-tube provided with draft-openings 7,
a damper-ring 8 being properly supported
upon the font-casing in order to coöperate
with the said openings 7 and a lever 9 pivot-
ally supported upon the font-casing having
one end connected to said damper-ring and its
other end provided with a damper-plate 10,
which is adapted to control the lower end of
said central draft-tube 6. By reason of this
construction the damper-ring and the damper-
plate 10 are caused to move simultaneously.
Before lowering the oxidizing member for the
purpose of extinguishing the flame the draft-
openings are of course closed, said openings
being again opened after the flame is extin-
guished in order to permit proper evapora-
tion of the liquid in the font.

Of course many absorbent materials can be
employed, as the wick in the font; but I pre-
fer to employ sections 11 of asbestos rope,
these sections being arranged vertically and
properly packed in the font. By reason of
the employment of said sections I am enabled
to obtain a substantially even evaporating-
surface, it being possible to cut the sections
of rope to the desired length, and the vertical
arrangement produces extremely satisfactory
capillary attraction. The draft-openings be-
ing in the center and also at the periphery of
the font, air is supplied in proper quantities
over the whole surface of absorbent mate-

rial, so that evaporation from said surface is
substantially uniform, and thus serves to uni-
formly heat the oxidizing device over the en- 70
tire surface of the latter.

For the oxidizing or catalytic material I pre-
fer to employ carded or otherwise finely-di-
vided asbestos wool impregnated with a proper
agent, such as copper oxid, this material be- 75
ing here shown as supported by a suitable
frame. The present frame comprises sepa-
rable sections 12 and 13, the peripheral ring
of one of which is adapted to fit within the
other thereof, and the ring of each section 80
supports a piece of fine wire mesh 14, the ox-
idizing or catalytic material being received be-
tween these meshes of wire-gauze and the
frame being conveniently held together by
thread (preferably of copper wire) 15, sewed 85
through the wire-gauze and through the as-
bestos wool. Upon the upper frame-section
12 is an outwardly-extending flange 16, which
when the frame is in lowermost position is
adapted to rest upon the upper edge of the 90
font-casing, the bottom of the said frame when
the frame is supported in said lowermost po-
sition being above the draft-openings 7.

The vertical standards 1 extend upwardly
above the font and are provided with verti- 95
cal slots 17, which have suitable angular ex-
tensions 18, 19, and 20. Pins 21, extending
outwardly from the frame supporting the ox-
idizing material, are confined in the said slots
17 and are adapted to enter the angular ex- 100
tension 18, and thus support the said frame
in its elevated position. Suitable handles 22
are also provided upon the said frame in or-
der to permit the same to be readily manipu-
lated, these handles being oppositely placed 105
and only one of them being here shown.

In fumigating by means of a gas it is of
course important that the gas be generated
rapidly in a large volume, so that the gas is
generated much more rapidly than it can es- 110
cape from the room being fumigated. If the
oxidizing material be supported a consider-
able distance above the surface from which
the alcohol evaporates, the production of gas
is necessarily slow. If, on the other hand, 115
the oxidizing material of the character of the
present be supported only a short distance
above the surface from which the alcohol is
evaporated, said material frequently causes
the alcohol-vapor to become ignited, and such 120
ignition is of course undesirable. In the pres-
ent construction the oxidizing material is sup-
ported upon and inclosed between wire-gauze
or perforated metal, fine copper wire-gauze
being preferable. This enables the said ma- 125
terial to be supported a very short distance
above the surface from which the alcohol is
evaporated without causing the alcohol-vap-
or to ignite, the action of said gauze to pre-
vent this ignition being well understood. In 130
the present machine, therefore, the oxidizing
material can be supported a very short dis-
tance above the wicks 11 and the formalde-
hyde gas is quickly produced in a large vol-

ume, there being no danger of ignition of the vapor.

I preferably provide the font with an outwardly-extending flange 23, upon which the flange 16 is supported, and place a ring of asbestos or like material 24 upon the supporting-surface of said flange 23, so that the said flange 16 can rest directly upon the asbestos or other packing ring, and thus prevent escape of vapor between the said flanges 16 and 23.

The smothering-plate 4 is provided with outwardly-extending pins 25, which are confined in the before-mentioned slots 17 and are adapted to enter the before-mentioned angular extensions 19 in order to cause the smothering-plate to be supported in elevated position. The smothering-plate is preferably dished, as shown, so that its lower edge can fit snugly upon the before-mentioned packing-ring 24, the smothering-plate having suitable cut-out portions at its lower edge to receive the pins 21, projecting from the frame which carries the oxidizing material. The smothering-plate is also preferably provided with handles 26. The water-pan 5 is provided with outwardly-extending pins 27, which are here shown as confined in the before-mentioned slot 17 and adapted to enter the angular extensions 20 in order to support said pan in proper position, the pan being also provided with handles 28. The said pan can be fixedly supported, if so desired, or it can be made integral with the smothering-plate and be adjustable, these being matters which can be varied at will without departing from my invention.

Preferably a chamber 29 is supported upon the present apparatus, said chamber being here shown as supported upon the inwardly-extending upper ends 30 of the before-mentioned standards 1, and this chamber is adapted to be employed for burning sulfur or other chemicals whose fumes it may be desired to liberate in the compartment being fumigated.

The present apparatus can be readily and cheaply made and assembled and can be readily transported and conveniently operated by unskilled persons.

By the use of the present apparatus a very large quantity of formaldehyde gas can be quickly generated, and, furthermore, the dry gas can be first generated, so that this dry gas can thoroughly penetrate materials in the compartment being fumigated, and then moisture is mixed with the gas in order to permit its full germicidal effects to be taken advantage of. In order to fill the font when the oxidizing member is in lowermost position, it is only necessary to lift one side of said member, the said member being thus tilted and affording a passage through which the alcohol or other liquid can be poured.

I am aware that minor changes in the construction, arrangement, and combination of the several parts of my device can be made and substituted for those herein shown and

described without in the least departing from the nature and principle of my invention.

Having thus described my invention, what I claim as new, and desire to secure by Letters Patent, is—

1. An oxidizing member of the character indicated comprising telescoping frame-rings, wire-gauze sheets upon said respective rings, oxidizing material between said gauze sheets, and a supporting-flange upon one of said rings and extending laterally therefrom; substantially as described.

2. An oxidizing member of the character indicated comprising a mass of finely-divided material of the character of wool impregnated with an oxidizing agent, and reticulated members between which said mass of material is confined; substantially as described. 85

3. In an apparatus of the character indicated, supporting-standards, a font supported thereon, an oxidizing member above said font and also supported upon said standards, and a vertically-adjustable smothering-plate also supported upon said standards; substantially as described. 90

4. In an apparatus of the character indicated, supporting-standards, a font supported thereon, an oxidizing member adjustably supported upon said standards, and a smothering-plate also adjustably supported upon said standards; substantially as described. 95

5. In an apparatus of the character indicated, a font having an open top, supports rising from said font, an oxidizing member supported upon said supports, and a water-pan above said oxidizing member and also supported upon said supports; substantially as described. 100

6. In an apparatus of the character indicated, a skeleton frame comprising supporting-standards, a font supported upon said standards, an oxidizing member supported upon said standards, and a water-pan also supported upon said standards; substantially as described. 105

7. In an apparatus of the character indicated, supporting-standards, a font supported thereon, an oxidizing member adjustably supported upon said standards, a smothering-plate also adjustably supported upon said standards and above said oxidizing member, and a water-pan above said smothering-plate; substantially as described. 115

8. In an apparatus of the character indicated, supporting-standards provided with elongated slots having angular extensions, a font, and an oxidizing member provided with pins received in said slots and coöperating with said angular extensions; substantially as described. 120

9. In an apparatus of the character indicated, supporting-standards, each of which is provided with an elongated slot having a plurality of angular extensions, a font, an oxidizing member having pins entering said slots and coöperating with said angular extensions, and a smothering-plate also having 130

pins received in said slots and coöperating with said angular extensions; substantially as described.

10. In an apparatus of the character indicated, a skeleton frame comprising supporting-standards, a font supported upon said standards, means for transforming vapor from said font into formaldehyde gas or the like, and a receptacle for chemicals also supported upon said standards; substantially as described.

11. In an apparatus of the character indicated, a font having an open top and a peripheral wall provided with draft-openings, a vertically-adjustable oxidizing member extending over the whole area of said open top of said font and adapted to seat closely upon said peripheral wall, means for supporting said oxidizing member in adjusted position above and spaced from said peripheral wall, and a damper for said openings in said peripheral wall; substantially as described.

12. In an apparatus of the character indicated, a font provided with a central draft-tube and also with peripheral draft-openings, dampers controlling said tube and said open-

ings, and connection between said dampers whereby they are caused to operate simultaneously; substantially as described.

13. In an apparatus of the character indicated, a font provided with a central draft-tube and also with peripheral draft-openings, a slide-damper coöperating with said peripheral openings, and a lever having one arm connected to said slide-damper and its other arm provided with a damper-plate controlling said tube; substantially as described.

14. In an apparatus of the character indicated, a font, and a plurality of vertically-arranged sections of rope of porous material packed in said font to produce a filler therefor and having their inner ends abutting against the font-bottom; substantially as described.

In testimony whereof I hereunto affix my signature, in the presence of two witnesses, this 24th day of February, 1903.

SETH M. MORRIS.
